UNITED STATES PATENT OFFICE.

PETER ORENDS, OF CEDAR RAPIDS, IOWA.

NEWSPAPER-HOLDER.

1,376,031.

Specification of Letters Patent. Patented Apr. 26, 1921.

Application filed March 2, 1920. Serial No. 362,712.

To all whom it may concern:

Be it known that I, PETER ORENDS, a citizen of Hungary, formerly Austria-Hungary, residing at Cedar Rapids, in the county of 5 Linn and State of Iowa, have invented certain new and useful Improvements in Newspaper-Holders, of which the following is a specification.

The object of this invention is to provide 10 a convenient holder for newspapers, more especially designed for use out of doors, or wherever currents of wind would blow the parts of a paper about and disarrange them.

The invention consists in providing a 15 light wire frame, to one side of which the folded side of the paper is attached, the frame serving to hold the paper straight and flat, and permitting its sheets to be turned over and perused like the leaves of a book.

20 In the accompanying drawing, forming a part of this specification, Figure 1 illustrates my improved newspaper holder, as in use. Fig. 2 is a view of the same, with the paper detached.

25 In the drawing, the numeral 5 denotes a rectangular frame formed of wire, the terminals of which meet at the middle to form a twisted-mid rib 6. A continuation of the 30 twisted part 7 serves as a shank, and to this is attached a suitable handle 8. To the ends of the frame as thus outlined, intermediate wires 9 are attached, and from side to side extend cross-wires 10, preferably twisted 35 into the midrib, as shown. The inside wires may be considerably lighter than the marginal wires, and where joined to them, and at the crossings, should preferably be soldered fast. The wire should be of material 40 which will spring considerably without permanent bends. This forms a light grid, easily held in the hand, and giving a stable back support for a newspaper spread over it.

At 11 the wire of the outer frame is expanded, and to it is pivoted a clamping wire

12. At 13 the wire is similarly expanded, 45 and to it is pivoted a stirrup 14 to engage the lower end of the clamping wire. The latter is provided with a slight projection at 15 to hold the stirrup in place when engaged. 50

The page of the paper shown in Fig. 1 represents a back page, rather than the front page, as the title would seem to indicate.

It will be evident that the pages may be turned over the clamping wire, and will be 55 in position for reading, by reversing the holder.

Near the upper corner of the frame to which the clamping wire is pivoted, is formed an eye 16, by which the holder may 60 be suspended, when not in use, the inclined paper hanging from its folded side flatly and neatly against the frame.

Having thus described my invention, I 65 claim:

1. A newspaper-holder, comprising a rectangular frame of wire formed as a grid, with a central, twisted midrib, a handle connected therewith, a clamping wire hinged to the frame near one corner, and a fastener 70 for the free end thereof attached to the opposite corner on the same side.

2. A newspaper holder, comprising a rectangular outer frame formed of wire, inter-twisted in the middle, lengthwise, and provided with a suitable handle, intermediate longitudinal wires of lighter gage connecting with the ends of the frame, similar cross-wires connecting with the sides of the frame, and threaded through the midrib, and a 75 clamping wire and fastener to hold the fold of the paper at one side of the frame. 80

In testimony whereof I affix my signature in presence of two witnesses.

PETER ORENDS.

Witnesses:

F. W. ARMSTRONG,
H. S. ROBERTSON.
